WEB FEEDING MEANS FOR ADJUSTABLE ROTARY IMPRINTERS

Dimitri L. Gorbatenko, San Francisco, Calif.

Application January 7, 1950, Serial No. 137,439

6 Claims. (Cl. 101—228)

1

This invention relates to new and useful improvements in web feeding means for adjustable rotary imprinters. Reference is made to my co-pending application Serial No. 214,879, filed March 10, 1951.

At the present time, it is standard practice to print labels and the like on a web of paper stock in large quantities at a single run of the press for the reason that setting up such a press is time-consuming and the labor cost makes it uneconomical to print a small quantity at one time. On the other hand, between the time that a stock of labels is printed and the stock is exhausted it may be necessary for the seller of the product to which the label is applied to change prices and vary ingredients or in other ways vary the substance of certain symbols commonly printed on such labels. Thus it is desirable to print up large quantities of labels at one time and leave blank spaces for such items as price, ingredients, and other symbols which may be subject to variation before the stock of labels is exhausted. The present invention has for its purpose the imprinting of the desired symbols in the blank space provided or the overprinting of new symbols in place of material already printed on the label. The present invention is for use on web stock and is of a rotary type. The term "label" as employed herein is intended to include other similar printed units of relatively short length.

One of the principal features and advantages of the invention is its adjustability. It will be understood that labels of various dimensions may be printed on paper webs. The present invention concerns an imprinter having a web-pulling mechanism accurately adjustable so that the distance which the web is advanced for each revolution of the drive shaft of the machine may be equalized with the exact length of the label.

Another feature of adjustability of the imprinter is that the position of the imprinted matter may be shifted longitudinally of the web, the machine being capable of such adjustment even while in operation.

Still another adjustment is a novel means for adjusting the distance between rolls through which the web is fed in order to accommodate varying thicknesses of paper and the like.

Still further objects and advantages of the invention relate to the adjustability of the cut-off mechanism and the interchangeability of such mechanism with a web rewind mechanism.

With the above and other objects and advantages in view, the invention consists in the matters hereinafter set forth and more particularly pointed out in the appended claims, reference

2

being had therein to the accompanying drawings, in which:

Fig. 1 is a longitudinal vertical section through the imprinter.

5 Fig. 2 is a section taken substantially along the line 2—2 of Fig. 1.

Fig. 3 is an enlarged section through the web pull mechanism taken substantially along the line 3—3 of Fig. 2.

10 Fig. 4 is a section taken along the line 4—4 of Fig. 3.

Fig. 5 is a fragmentary view of an adjustable bearing block for an impression cylinder, together with associated mechanism.

15 Fig. 6 is an elevation of adjustable sectors for the web pull mechanism.

Fig. 7 is a schematic view of a pair of labels, one being shown before and the other after imprinting.

20 Fig. 8 is an elevation of the cut-off mechanism.

It will be understood that the imprinter which is the subject of the present invention is used to imprint labels 9, which have been previously printed on a web 10 of paper stock wound in a roll 11, each label being in very close proximity to the adjacent label. It is further understood that each label in web 10 will ordinarily be of exactly the same length as every other label in the web and that the space between labels will not vary, but that occasionally the dimensions of the labels will vary gradually as the result of certain factors hereinafter discussed and that there may be a gap in the spacing between labels by reason of the press on which the labels were originally printed having been shut down for adjustment or for other reasons. Another variable factor entering into the design of the imprinter is that labels of various lengths may be imprinted and the feed of the web through the imprinter is adjustable for different lengths of labels.

45 The imprinter which is the subject of the invention consists of several parts integrated in operation and each separately described herein, these parts being:

Web guide mechanism

Inking mechanism

Printing mechanism

Web pull mechanism

50 Cut-off mechanism

Web rewind mechanism

Web guide mechanism

55 The web guide mechanism is of standard construction and functions to guide the web 10 from roll 11 to the printing mechanism. Labels 9a

have been printed on the web in a press in an operation prior to the imprinting accomplished by the present invention. Web 10 is wound on roll 11 about a spindle 12. Said spindle 12 is journaled in brackets 13 carried by main frame 14 of the imprinter so that new rolls may be installed as required and empty spindles removed after all of the web has been imprinted. The web first passes through tension rolls 16 and 17, roll 16 preferably having a rubber peripheral surface and the other roll 17 having a steel periphery. Tension rolls 16 and 17 are not power driven and their function is to keep that portion of the web extending interiorly of the machine under tension. Guide roll 18 is provided with rings 19 which engage the edges of the web and center the web with respect to the machine, it being understood that rings 19 are adjustable for webs of different widths. The web also passes under second guide roll 21 and thence up and around the top of impression cylinder 22, which is part of the printing mechanism and is herein-after described in greater detail.

Inking mechanism

The inking mechanism is likewise conventional in structure. It will be understood that said mechanism is only one of several types that might be employed. Ink is deposited in well or fountain 23 and applied to fountain roll 24, the thickness and evenness of deposit of ink being controlled by adjustable blade 26. The ink is then transferred, as well understood in the art, to vibrating doctor roll 21, then to distributing roll 28, and thence to form roll 29.

Printing mechanism

Immediately above the impression cylinder 22 is plate cylinder 31, the web 10 passing between these two cylinders. One of the important features of the construction of the plate cylinder 31 is the fact that the rubber type plate 32, attached thereto by adhesive material and hence removable therefrom, and the words, figures or other symbols of said type plate may be varied as desired. Ink is transferred to plate 32 from roll 29 by contact. As illustrated in the accompanying drawings, type plate 32 does not extend completely around the circumference of plate cylinder 31 but only one-quarter therearound. It is desirable that the circumferential length of plate 32 be equal to the length of the individual labels 9 or other units previously printed on web 10. Cylinder 31 is power driven, as herein-after described, and rotates continuously at uniform speed. During each revolution of plate cylinder 31, the plate 32 contacts web 10 as it is drawn over impression cylinder 22 and thereby imprints the desired symbols 9c such as price, ingredients, etc., on the label in the exact location desired. Fig. 7 shows a label 9a before, and a label 9b after, imprinting. When labels of different lengths are to be imprinted, the circumferential length of plate 32 is varied accordingly. The upper limit of the length of plate 32 is the circumference of cylinder 31, but it will be understood that plates of considerably shorter length may be used without interchanging cylinder 31 for a cylinder of different diameter. The radius from the central axis of cylinder 31 to the periphery of plate 32 is greater than the radius from said axis to the periphery of cylinder 31. Hence when that portion of cylinder 31 which is not covered by plate 32 is over impression cylinder 32, there is no contact with web 10, said web being

kept tight against the surface of cylinder 22 by tension rolls 16-17 and tension rolls 33 of the Web Feed Mechanism.

It is desirable to feed web 10 a distance equal to the length of label 9 while plate 32 is passing over impression cylinder 22, and then to hold the web stationary while the portion of the plate cylinder 31 which is not covered by plate 32 is passing over the impression cylinder 22. In this way, any label having a length less than the circumference of cylinder 31 may be imprinted and labels 9 may be consecutively arranged on web 10 without any gap between consecutive labels. Web 10 is fed a distance equal to the length of one label 9 for each revolution of plate cylinder 31, and remains stationary when plate 22 is not in contact with the web. The feeding of the web the required distance is one of the important features of the invention and is hereinafter described.

The shafts of each of rolls 16, 17, 18, 21, 22, 24, 27, 28, 29 and 31 is journaled in stationary vertical side plates 34 fixed to the main bed 14 of the machine. Cylinder 22 is vertically adjustable with respect to cylinder 31 to accommodate webs of various thicknesses, to compensate for variations in thickness of plates 32, in order to back off cylinder 31 from contact with plate 32 when the machine is being turned over with no web installed, and for other reasons. The adjustability of cylinder 22 is accomplished by journaling each end of shaft 36 of said roll in a bearing block 37. Bearing blocks 37 are located at each side of the machine and are vertically slidable in ways in side plates 34. Springs 38 between the tops of blocks 37 and the stationary side plates 34 bias the blocks downwardly. Cams 39 located bearing against the lower ends of blocks 37 thus raise the blocks 37 in their ways and with the blocks cylinder 22, against the pressure of springs 38. Cams 39 are eccentric and are mounted on rotatable shafts 41 journaled in side plates 34 and carrying knobs 42 at either or both ends. Manipulation of knob 42 causes rotation of shaft 41 and this rotates cheeks 43 which bear against the lower edges of blocks 37. The feature of this type cam is the fact that the point of bearing of cheek 43 is immediately above the center of shaft 41 and hence there is no tendency of the cam to back up. No detent or lock is required to hold cam 39 in proper position of adjustment once it is set.

The shafts of rolls 24, 28 and 31 are all power driven off main drive shaft 44. All of said shafts are at the same elevation and each bears skew bevel gears 46 meshing with a corresponding skew bevel gear 47 keyed to drive shaft 44.

Web pull mechanism

The web feeding mechanism is designed to feed the web 10 a distance equal to the length of a label 9 or the exact desired length between two identical symbols 9c to be printed on the web and to so feed the web only when the plate 32 is passing over the impression cylinder 22 and not to feed the web during the remainder of each revolution of cylinder 31. Therefore the web 10 passes over pressure roll 51 and is held in contact therewith by spring-biased tension rolls 33 which permit feeding of the web only when pressure roll 51 is rotating. Said pressure roll 51 preferably is provided with a rubber surface. Immediately above pressure roll 51 is a pull shaft 52 bearing adjustable sectors 53 and 54, which are knurled, milled or otherwise roughened along their arcuate surfaces 55 so that when said arcu-

ate surfaces contact pressure roll 51 they bite into the rubber surface thereof and roll 51 is rotated. It will be noted that pull shaft 52 is positively driven off main drive shaft 44 and hence continuously rotates in synchronism with the shaft of cylinder 31.

There are at least two sectors 53—54, the angular position of at least one of which with respect to shaft 52 being adjustable. Set screw 56 or other means may be used to lock said sector 54 for rotation with shaft 52, and sector 53 is fixed by pin 56a so that the leading edge of sector 53 with respect to the leading edge of plate 32 is defined and the feeding of the web 10 commences at the precise time that plate 32 comes in contact with a label 9. Said sector 54 is made angularly adjustable so that the total circumferential length of arcuate surfaces 55 may be made exactly equal to the length of label 9. For labels of greater or lesser length, sector 54 may be angularly adjusted. The radius from the center of shaft 52 to the periphery 55 of sectors 53—54 is equal to the radius from the center of the shaft of cylinder 31 to the periphery of plate 32 and the diameters of pressure roll 51 and impression cylinder 22 are equal.

Since web 10 is only advanced when pressure roll 51 is rotated, and since pressure roll 51 is only rotated when sectors 53—54 are in contact therewith, web feed may be accurately adjusted by angular adjustment of sector 54 to feed the web the length of one label, which will ordinarily also be the length of plate 32. Pressure roll 51 is made vertically adjustable by cam 57 which is identical in structure with cam 39, said cam 57 bearing against the lower surface of vertically slidabie bearing blocks 58 mounted in carriage 59. Said cam 57 is turned about its shaft 61 by knob 62 causing cheek 63 to raise or lower blocks 58 in which roll 51 is journaled, springs 60 biasing blocks 58 downwardly and forcing them against cheeks 63. Cam 57 remains fixed in position without the necessity of locking means in the same manner as cam 39. This feature of adjustability permits proper operation regardless of wear of roll 51. It also permits roll 51 to be backed down out of contact with sectors 53—54 and hence permits the imprinter to turn over without pulling the web when this operation is desired, as when other portions of the machine are being adjusted.

Carriage 59, in which roll 51, tension rollers 83 and shaft 52 are journaled, is horizontally slideable in ways in side plates 34 and top frame member 64. Nut 66 is fixed to carriage 59 and said nut engages longitudinally disposed, horizontal threaded shaft 67. As threaded shaft 67 is turned, carriage 59 may be caused to move longitudinally of the machine. Rotation of shaft 67 may be accomplished in various ways. As illustrated in the accompanying drawings, one end of shaft 67, which is held against longitudinal movement, bears a worm wheel 68 meshing with transverse worm shaft 69. Hand wheel 71 turns worm shaft 69 and hence moves carriage 59.

The purpose of the carriage adjustment is to improve the flexibility of the machine. The distance between the center of shaft 52 and the axis of cylinder 31 should be a multiple of the length of a label 9, said distance being measured longitudinally along the web. Table 72 on which web 10 rests may be used to prevent sagging of the web, or the web may be otherwise supported either to prevent or accurately control the amount of sagging. Carriage 59 is thus made

adjustable so that a symbol 9c will be imprinted in the exact spot of the web desired, and hence the relative position of the symbol impressed on the web may be adjusted by moving carriage 59.

Under ideal conditions, each label 9 will be of the same length and all will be equally spaced. However, if the press on which the labels were originally printed was stopped for any reason or if there is an accumulation of extremely small differences between the feed of web 10 and the lengths of labels 9, then it may be necessary from time to time to move carriage 59 to bring symbol 9c imprinted on the label into registry with the exact spot desired.

Skew bevel gear 73, which meshes with gear 14 on shaft 52, is keyed to a long keyway 75 in main drive shaft 44 and bevel gear 73 is so mounted abutting bracket 77 extending from carriage 59 that it moves longitudinally of shaft 44 as carriage 59 moves and thus shaft 52 is power driven at all times. Movement of carriage 59 may be made even while the machine is in operation.

Cut-off mechanism

The imprinter illustrated in the accompanying drawings shows both a cut-off mechanism and a rewind mechanism, which may be used alternatively. The purpose of the cut-off mechanism is to cut labels 9 to size exactly on the line dividing adjacent labels, after the web 10 has passed through the pull mechanism. The cut-off mechanism employs an oscillatable knife 81 which shears off the web 10 against stationary cutting edge 82. Holdown 83 biased by spring 84 holds the web stationary while it is being severed. Knife 81 is driven by cam 85 on main drive shaft 44 and it is pivoted midway between its ends so that when the high portion of cam 85 contacts the adjacent part of knife 81 the knife operates to shear the web. It is necessary in this type cut-off mechanism that the cutting operation be performed while web 10 is stationary, or, in other words, while sectors 53—54 are not in engagement with roll 51. Cam 85 is timed to cut the web when the latter is stationary.

In order that knife 81 cut exactly at the dividing line between adjacent labels, the cut-off mechanism is incorporated in horizontally slideable carriage 86 sliding in ways in side plates 34 and top frame member 64 in the same manner as carriage 59 for the web pull mechanism is slideable. Carriages 59 and 86 are adjustably linked together so that the distance therebetween may be varied to cut off the labels along the desired line. The distance, measured longitudinally along web 10, between the line of contact between roll 51 and sectors 53—54 and knife 81 will ordinarily be a multiple of the length of a label 9, and the operator will so adjust the position of knife 81 with respect to carriage 59. Hence links 87 connecting carriages 59 and 86 are provided with a slot 88. Bolt 89 which is threaded into carriage 86 is slideable within said slot 88 until tightened. After proper adjustment has been made, bolt 89 is tightened and the two carriages 86 and 59 are locked together for unitary movement along their respective ways when the operator turns hand-wheel 71. Hence when, from time to time, carriage 59 must be moved, knife carriage 86 moves with it and once the distance between carriages 59 and 86 has been adjusted for the particular length label being imprinted, it is not necessary to readjust the same if the web pull mechanism 75 must be moved.

Rewind mechanism

It is sometimes necessary to rewind web 10 on a new roll 91 after it has been imprinted instead of cutting off individual labels. In such event, the cut-off mechanism is held inoperative. Web 10 is directed over guide roll 92 and thence wound on roll 91 about spindle 93 removably held in brackets 94 on main frame 14. One end of spindle 93 is provided with a sprocket 96 which is connected by roller chain 97 to sprocket 98 on shaft 99. The shaft of pressure roll 51 is likewise provided with a sprocket 101, and this is connected by roller chain 102 to a sprocket 103 on shaft 99, there being a slip clutch 104 between sprocket 103 and shaft 99. Chain 102 is held tight by take-up sprocket 106 which meshes therewith, arm 107 on which sprocket 106 is mounted being biased by spring 108 so as to hold chain 102 tight, but nevertheless permitting carriage 59 to be moved back and forth on its ways without interfering with the driving action of chain 102. The purpose of slip clutch 104 will be understood when it is considered that the distance which web 10 is wound on roll 91 for one rotation of spindle 93 is considerably greater when the roll is thick than when it is thin. The purpose of the rewind mechanism is to wind web 10 on roll 91 as rapidly as it is fed through the web pull mechanism.

Operation

It will be assumed that a series of labels 9a have been printed on web 10 in a previous operation on another press. It will further be assumed that each of said labels is exactly three inches in length and that there is no blank space between adjacent labels. In order to imprint a desired symbol 9c in registry with a specific spot on the label, said symbol is set in rubber type type on plate 32 which is fastened to plate cylinder 31. Plate 32 will be three inches or less in length, but the circumference of cylinder 31 may be considerably greater than three inches, in this instance twelve inches or four times the length of label 9. After the inking mechanism has been properly set up and web 10 threaded through the various rolls and cylinders of the press as shown in Fig. 1, the operator is ready to make the various adjustments required for proper imprinting.

The first adjustment involves the setting of sector 54. Assuming that the circumferential length of each sector is two and one-half inches, then for a label three inches in length, sector 54 is set so that the aggregate circumferential length of the surfaces 55 of sectors 53 and 54 is three inches—i. e. the sectors overlap two inches. With this setting of sector 54, the web should be pulled the length of one label 9 for each revolution of shaft 44, and this feeding of the web will occur when sectors 53—54 are in contact with the rubber surface of roll 51. This movement is timed to occur while plate 32 is over cylinder 22. For the remainder of the revolution of cylinder 31, there is no movement of web 10. Thus, if the circumference of roll 31 is twelve inches, and the length of label 9 is three inches, the web will be fed one-fourth of the time and remain stationary three-fourths of the time. It will be found in practice, however, that due to slippage, stretching of the web, varying atmospheric conditions affecting the tension of the web, inertia, and other factors, a slight difference between the length of web pull and the length of labels may exist. The operator must adjust the setting of sectors 53—54 to compensate for these differences.

The next adjustment involves positioning the symbol 9c in the exact spot on label 9 which is required. This adjustment is made by moving carriage 59 horizontally, which results in shifting each label 9a on web 10 relative to the line of contact between plate 32 and cylinder 22. Theoretically the length of web between said line of contact and the line of contact between sectors 53—54 and roll 51 should be a multiple of the length of a label 9 and initial adjustment should be so made. However, due to variations heretofore discussed, it may be necessary to move carriage 59 toward or away from the printing mechanism in order to register the symbol 9c on the exact spot on label 9b which is required.

Cam 39 is adjusted so that the printing is of the desired intensity. Manipulation of knob 42 raises and lowers impression cylinder 22 and accomplishes this result. Variations in thickness 20 of web, etc., may be compensated for in the same manner.

Cam 57 is adjusted so that sectors 53—54 properly engage the resilient surface of roll 51.

If the cut-off mechanism is to be used, bolt 89 25 is loosened and knife 81 positioned the required distance from roll 51 so that labels 9 are severed exactly on the lines dividing adjacent labels.

After the machine has been in operation, it 30 may be found that the symbol 9c is no longer in the exact spot desired. This may be due to two factors—improper initial setting of sector 54 or the occurrence of a gap in the web resulting from a shutdown in the press in which the web was originally printed, slippage, or the like. The 35 first irregularity is corrected by adjustment of sectors 53—54. The latter is corrected by shifting carriage 59 even while the machine is in operation to relocate symbol 9c in the proper spot.

It will thus be seen that the instant invention 40 comprises an imprinter for printing desired symbols in blank spaces provided in web stock or for overprinting new symbols in such spaces. The machine is extremely flexible and adjustable in that labels or the like of various lengths may be 45 imprinted without changing the diameters of the rolls over which the web passes; a simple and easily-accomplished adjustment adapts the machine to a new length of label. The adjustability is provided by intermittently advancing the web a distance equal to the length of one label or the like for each revolution of the drive shaft of the machine. The position of the symbol imprinted is also easily shiftable longitudinally of the web, even while the machine is in operation. The 50 invention further envisions a simple adjustment of the clearance between rolls, the cam which accomplishes this adjustment being so constructed that no detent or lock is required to hold the roll in a position of adjustment. Finally, the invention provides for adjustability of the cut-off mechanism and the further alternative provision of a rewind mechanism which operates only when the web is advanced.

It will be understood that whereas a preferred 55 embodiment of the invention has been described and illustrated, changes may be made therein without departing from the spirit of the invention and scope of the appended claims.

What is claimed is:

1. In a rotary imprinter for web stock, adjustable feed means for intermittently advancing said web through the machine an adjustable, fixed distance comprising, a first shaft rotatably driven, a plurality of sectors mounted for rotation on said first shaft, said sectors having rough-

ened arcuate surfaces, at least one of said sectors being angularly shiftable with respect to another of said sectors about the axis of rotation of said sectors, whereby the aggregate circumferential length of the arcuate surfaces of said sectors may be adjusted relative to said adjustable, fixed distance in infinitely fine gradations, a web-advancing pressure roll substantially wider than said web with which said web is in contact, said pressure roll having a resilient peripheral zone of uniform radius of curvature engageable with said arcuate surfaces and rotatable upon rotation of said sectors, said sectors being the sole means for rotating said pressure roll, said zone being remote from the area of contact of said pressure roll with said web, and means for advancing and retracting said pressure roll and said sectors relative to each other for engagement and disengagement with one another, said last-mentioned means comprising a cam shaft having its axis located parallel to a plane, the elements of which are the various positions of adjustment of the axis of the shaft of said pressure roll, and a circular cam cheek eccentric to the axis of said cam shaft and fixed thereto, said cheek being engageable with mounting means for said pressure roll to advance and retract said pressure roll.

2. An adjustable device for transmitting continuous rotary motion from a driving member into intermittent rotary motion of a driven member, and wherein the angular rotative movement of said driven member per revolution of said driving member is adjustable to any desired degree in infinitely fine gradations, said device comprising, first means fixed for rotation with said driving member, at least two parallel cams mounted for rotation with said first means, each of said cams having an elevated, roughened, arcuate peripheral working surface, at least one of said cams being angularly shiftable relative to the other to adjust the circumferential distance between the leading edge of the working surface of the foremost cam and the trailing edge of the working surface of the other cam to any desired length, and resiliently surfaced, cylindrical second means of uniform radius throughout its periphery fixed for rotation with said driven member against which the working surfaces of said cams are arranged to bear, the angular rotative movement of said second means per revolution of said first means being solely dependent upon and adjustable by adjustment of said circumferential distance between the leading edge of the foremost cam and the trailing edge of the working surface of the other cam.

3. In a rotary imprinter for web stock, adjustable feed means for intermittently advancing a web through the machine an adjustable, fixed distance comprising, a first shaft, means for rotatably driving said first shaft, a plurality of sectors mounted for rotation on said first shaft, at least one of said sectors being angularly shiftable with respect to another of said sectors relative to the axis of rotation of said sectors, whereby the aggregate circumferential length of the arcuate surfaces of said sectors may be adjusted relative to said adjustable, fixed distance in infinitely fine gradations, and a web-advancing pressure roll, said pressure roll being engageable with all of said sectors in a zone remote from the zone of passage of said web and intermittently rotatable thereby, said pressure roll having the same radius of curvature throughout its periphery, said pressure roll being driven solely by said sectors.

4. In a rotary imprinter for web stock, adjustable feed means for intermittently advancing a web an adjustable, fixed distance, comprising, a first shaft, means for rotatably driving said first shaft, a plurality of sectors mounted for rotation on said first shaft, said sectors having roughened arcuate surfaces, at least one of said sectors being angularly shiftable with respect to another of said sectors about the axis of rotation of said sectors, whereby the aggregate circumferential length of the arcuate surfaces of said sectors may be adjusted relative to said adjustable, fixed distance in infinitely fine gradations, and a web-advancing pressure roll, said pressure roll having a resilient peripheral zone engageable with said arcuate surfaces and rotatable upon rotation of said sectors, said zone being remote from said web, said resilient peripheral zone having the same radius of curvature throughout its periphery, said pressure roll being driven solely by said sectors.

5. Adjustable means for transmitting continuous rotary motion from a first member into intermittent rotary motion of said second member, comprising, first means fixed for rotation with said first member, second means fixed for rotation with said second member, a zone of engagement and a zone of disengagement on the periphery of said first means, said zone of engagement being roughened and elevated above said zone of disengagement, the relative effective circumferential length of said zones of engagement and disengagement being adjustable in infinitely small gradations, a cooperating resilient peripheral zone extending around the periphery of said second means arranged to be rotated by said first means when said zone of engagement is in engagement therewith, said resilient peripheral zone being of uniform radius throughout its periphery, said first means being the sole means for rotating said second means, the relative angular movement of said second means per revolution of said first means being manually adjustable in infinitely small gradations by corresponding adjustment of the aggregate effective circumferential length of said zone of engagement engageable with said peripheral zone.

6. Means according to claim 5 in which said first means is an adjustable cam, said zone of engagement is a roughened high dwell on said cam, and said second means is a resilient-surfaced roll into which said zone of engagement is arranged to bite.
